[57] **CLAIM**

The ornamental design for a portable tubular cooler for
canned beverages, as shown and described.

DESCRIPTION

FIG. 1 is a perspective view of a portable tubular cooler
for canned beverages showing my new design;

FIG. 2 is a perspective view of an alternate embodiment
of FIG. 1;

FIG. 3 is a front elevational view thereof;

FIG. 4 is a right side elevational view thereof, the oppo-
site side being a mirror image;

FIG. 5 is a right side elevational view of FIG. 2, the
opposite side being a mirror image;

FIG. 6 is a rear elevational view thereof;

FIG. 7 is a top plan view thereof, the opposite side
being a mirror image;

FIG. 8 is a perspective view of an alternate embodiment
of FIG. 1; and,

FIG. 9 is a perspective view of an alternate embodiment
of FIG. 1.

The undisclosed front, rear and top views of FIG. 2 are
similar to those of FIG. 1.

FIG. 1

FIG. 2

FIG. 3

FIG. 4

FIG. 5

FIG. 6

FIG. 7

FIG. 8

FIG. 9
